DESIGN FOR RUFFLING OR COLLARETTE.

Design No. 13,617, dated February 13, 1883.

UNITED STATES PATENT OFFICE.

HERMAN ROSENTHAL, OF NEW YORK, N. Y.

DESIGN FOR RUFFLING OR COLLARETTE.

SPECIFICATION forming part of Design No. 13,617, dated February 13, 1883.

Application filed December 20, 1882. Term of patent 34 years.

To all whom it may concern:

Be it known that I, HERMAN ROSENTHAL, a citizen of the United States, residing at New York, in the county and State of New York, have invented and produced a new and original Design for Ruffling or Collarettes, of which the following is a specification, reference being had to the accompanying drawing.

This invention relates to the design for ruffling or collarettes, consisting of a series of fan-shaped sections, which impart to the article a novel and ornamental appearance.

The drawing represents a perspective view of a collarette ornamented according to my invention.

In this drawing, the letter A designates the band to which the ruffling B is attached. This ruffling is ornamented by a series of fan-shaped

sections *a*, as shown. When the ruffling is made in the shape of a collarette, as shown in the drawing, the fan-shaped sections *a* a** at the ends are spread open and rounded off at the edges, as shown.

What I claim as new, and desire to secure by Letters Patent, is—

The design for rufflings or collarettes, consisting of the fan-shaped sections *a a*, formed on the body of the article, as shown and described.

In testimony whereof I have hereunto set my hand and seal in the presence of two subscribing witnesses.

HERMAN ROSENTHAL. [L. S.]
